UNITED STATES PATENT OFFICE.

HARRY T. WHITE, OF DETROIT, MICHIGAN.

THREADING-TOOL FOR AUTOMATIC MACHINES.

1,281,455.

Specification of Letters Patent. Patented Oct. 15, 1918.

Application filed August 27, 1917. Serial No. 188,422.

To all whom it may concern:

Be it known that I, HARRY T. WHITE, a citizen of the United States of America, residing at Detroit, in the county of Wayne and State of Michigan, have invented certain new and useful Improvements in Threading-Tools for Automatic Machines, of which the following is a specification, reference being had therein to the accompanying drawings.

10 The invention relates to threading tools of that type in which a collapsible tap or die is engaged with the work and on completion of the threading operation is automatically released therefrom. In the present 15 state of the art tools of this character have been devised comprising a head carrying a series of radially adjustable jaws to which the coöperating sections of the threading tools or chasers are secured. Means is also 20 provided for moving the jaws correspondingly from a working to a work-releasing position, and the release is effected automatically by stored power and a trip operated upon the completion of the work.

25 The accuracy of the work is dependent upon the accuracy of movement of the chasers and this in turn is dependent upon the accuracy of the guides. Usually the chaser-blocks are mounted on a T-shaped 30 jaw member which slidably engages a correspondingly-shaped groove in the head of the tool, but such constructions are open to various objections. In the first place, it is difficult with such a construction to obtain 35 the accuracy required for good work; and second, it is practically impossible to form hardened bearing surfaces, and consequently the wear incident to use soon renders the tool inaccurate.

40 It is the object of the present invention to eliminate these defects, first, by a construction which can be easily manufactured and with a high degree of accuracy; and second, by forming the structure of hardened metal which is ground to exact size. To this end the invention comprises the 45 novel construction permitting of such manufacture as hereinafter set forth.

In the drawings:

50 Figure 1 is a sectional elevation of the tool;

Figs. 2 and 3 are cross-sections on line 2-2 Fig. 1, showing the parts in different positions of adjustment;

55 Fig. 4 is an elevation of the cam, showing

the engagement of the jaw member therewith;

Figs. 5 and 6 are cross-sections on line 5-5 Fig. 4, showing respectively the work-engaging and releasing positions of adjustment.

A is a head which, as shown, is separate from the shank B and is secured thereto by set-screws C. D is an auxiliary head tele- 65 scopically engaging the head A to be longitudinally movable thereof but rotatively fixed thereto. As shown, the head A has an annular portion A' within which a cylindri- 70 cal portion D' of the head D fits. E are headed screws passing through apertures in the end of the head A and engaging the portion D' of the head D, and F are springs surrounding the screws E in a counterbore in the head A, one end of said springs abutting 75 against the head on the screw and the other against the shoulder of the counterbore. Thus the heads A and B are held from relative rotative movement, while the springs F yieldably hold the same from longitudinal 80 movement.

The auxiliary head D is provided with a portion D² of larger diameter than the portion D' and separated from the portion A' of the head A to form an annular groove therebetween. In this annular groove is 85 arranged an annular cam member G, the cams H thereof being arranged on the outer side and being located in a groove I in the portion D² of the head D. J are radial bores in the head D, which intersect the 90 groove I. K are radial slots of lesser width than the diameter of the bores J and extending therefrom outward through the end of the head D. The bores J receive cylindrical blocks or jaw members L, to which 95 are attached the chaser-blocks M, which latter are of a width to fit the radial slots K. The joint between the chaser-blocks and the jaws L is formed by a slot L' in the jaw for receiving the inner edge of the chaser-block, and a clamping bolt N, together with the dowel pin O, serves to hold the parts in 100 fixed relation. The blocks L (Fig. 5) are also provided on their inner sides with grooves P for engaging the cams H on the 105 annular cam member G.

The construction as thus far described is one which permits of forming the blocks L as well as the chaser-blocks M of hardened metal, and the head D in which the bores 110

J and slots K are formed can also be of hardened metal. The parts are ground to an exact fit, which operation can be easily performed inasmuch as the bores J are 5 round in section and the slots K have flat parallel sides. Such grinding would not, however, be possible if in place of this construction T-shaped slots were used. The blocks L are easily ground to fit the slots 10 K. Thus accuracy in construction is obtained.

The position of the chaser-blocks is determined by the rotative adjustment of the cam G, and to secure accuracy in this adjustment I employ the following construction: Q is a latch-pin slidably mounted in the head A and adapted to engage a socket R in the cam G to lock the chaser-blocks in their working positions of adjustment. 15 The socket R is adjustable in relation to the cam G by being placed in an elongated aperture S in said cam and held in the desired position of adjustment by opposed set-screws S' and S''. Thus by adjusting these set-screws the locking position of the cam may 20 be altered to obtain a predetermined position of adjustment of the chaser-blocks. The locking-pin Q is formed with a collar Q' thereon which fits the bore in the head A. A 25 spring T is sleeved upon the shank of the pin between this collar and a bushing T' having a threaded engagement with the bore, said bushing performing the double function of a spring abutment and a guide 30 for the pin. Thus the tension of the spring 35 will yieldably force the pin Q outward so that the instant that the socket R comes in registration therewith the pin will snap into engagement. The pin may, however, 40 be disengaged by a relative longitudinal movement of the heads A and D, and when so disengaged the cam G will be free for rotative adjustment, which will move the blocks L and chaser-blocks M so as to disengage 45 the latter from the completed work.

It is desirable to provide means for automatically actuating the cam to its releasing position, and this can be accomplished by a spring,—but as heretofore constructed the 50 assembly of the parts with the spring is a difficult operation. I have avoided the difficulty by placing the spring in an open segmental groove in the cam member G and retaining it in this position by a sleeve member 55 which may be longitudinally adjusted upon the heads A and D. As shown in detail in Fig. 2, U is the segmental slot in the cam member G; V is an abutment block fitting within the slot U and secured to the portion D' of the head D by bolts V'; W is a spring which is of segmental form to fit 60 within the slot U, the ends being provided with bearing blocks W' respectively bearing against the block V and the opposite 65 end of the slot U; X is a sleeve for fitting

over the heads A and D and forming a cover for the groove U; and Y is a handle for manually rotating the cam to set the same in operative position, said handle passing through an aperture in the sleeve X and serving to hold the same in position to cover the slot. 70

The construction described is one which can be easily manufactured with a high degree of accuracy. It is also a simple construction to assemble and the fact that all of the parts subject to wear are formed of hardened metal will greatly increase the life as well as maintain the accuracy of the construction. In use, the chaser-blocks are 75 adjusted to operative position by manually rotating the cam G through the handle Y until the locking pin Q snaps into engagement with the socket member R. In this position the threading operation is performed upon the work, the head A being drawn longitudinally so as to compensate for the spiral pitch of the thread. At the completion of the machining operation, a stop (not shown) arrests further longitudinal movement of the head A, whereupon the head D is drawn away from the head A against the tension of the springs F, and this movement will also disengage the pin Q from the socket R, whereupon the spring 80 W will quickly rotate the cam to its initial position thereby releasing the chaser-blocks 85 from the work. 90

What I claim as my invention is:

1. In a threading tool, the combination of 100 a head having a series of radially-arranged apertures therein each comprising a slot portion having parallel sides and a cylindrical portion of greater diameter, said head having a groove therein which intersects said cylindrical aperture, chaser-blocks fitting said slots having parallel walls, cylindrical guide-blocks fitting said cylindrical apertures and rigidly secured to said chaser-blocks, a rotary cam fitting the groove and 105 having portions engaging bearings on said cylindrical blocks to simultaneously actuate the same toward and from the axis of the head, a lock for holding said cam in one position of its adjustment, and a spring for 110 actuating said cam rotatively when released from said lock.

2. In a threading tool, the combination with a head, of a series of chaser-blocks 115 engaging radial guide bearings in said head, a rotary cam for actuating said chaser-blocks in their radial bearings, a spring for actuating said cam rotatively, located in a peripheral groove in said head, and a sleeve 120 on said head for covering said groove and retaining said spring.

3. In a threading tool, the combination with a head and radially-movable chasers mounted therein, of a rotary cam member 125 for operating said chasers engaging a pe- 130

ripheral groove in said head, said rotary member being itself peripherally slotted, an abutment in the peripheral slot of said rotary member secured to said head, a spring 5 arranged between said abutment and the end of the slot in said rotary member, and a sleeve surrounding said head forming a cover for the slot and a retainer for said spring.

10 4. In a threading tool, the combination with a head and a series of radially-adjust-

able chaser-blocks therein, of a rotary cam member for actuating said chaser-blocks, engaging a peripheral groove in said head, a spring for actuating said cam member also 15 located in said groove and peripherally insertible therein, and a sleeve surrounding said rotary cam member forming a cover for said groove and a retainer for said spring. 20

In testimony whereof I affix my signature.
HARRY T. WHITE.
